UNITED STATES PATENT OFFICE.

JOHN C. MILLER, OF CINCINNATI, OHIO.

DESIGN FOR A WATCH-CHARM.

SPECIFICATION forming part of Design No. 36,446, dated July 21, 1903.

Application filed May 13, 1903. Serial No. 157,022. Term of patent 7 years.

To all whom it may concern:

Be it known that I, JOHN C. MILLER, a citizen of the United States, residing at Cincinnati, in the county of Hamilton and State of Ohio, have invented a new, original, and ornamental Design for Watch-Charms, the features of which are shown in the accompanying drawing, making a part of this application.

10 The drawing is a plan view of my charm, showing the features of ornamentation.

Having described my invention, I claim—
The ornamental design for a watch-charm as shown.

In testimony whereof I have hereunto set my hand.

JOHN C. MILLER.
